DESIGN FOR A VELOCIPED

Harold L. van Doren and John G. Rideout,
Toledo, Ohio, assignors to The American-
National Company, Toledo, Ohio, a corporation
of Ohio

Application June 12, 1935, Serial No. 57,246

Term of patent 7 years

To all whom it may concern:

Be it known that we, Harold L. van Doren and John G. Rideout, both citizens of the United States of America, residing at Toledo, in the county of Lucas, in the State of Ohio, have invented a new, original, and ornamental Design for a Velocipede, of which the following is a specification, reference being had therein to the accompanying drawing, forming a part thereof, where-

Fig. 1 is a front perspective view of a velocipede, showing our new design;

Fig. 2 is a rear perspective view; and

Figure 3 is a fragmentary sectional view taken substantially on the line 3—3 of Figure 2.

We claim:

The ornamental design for a velocipede substantially as shown.

HAROLD L. VAN DOREN.

JOHN G. RIDEOUT.
